CONTROL APPARATUS FOR REVERSIBLE MOTORS

Malcolm G. Shoemaker, Abington, Pa., assignor to Philco Corporation, Philadelphia, Pa., a corporation of Pennsylvania

Application April 28, 1944, Serial No. 533,188

6 Claims. (Cl. 172—239)

1

This invention relates to a novel system for controlling a reversible motor, and more particularly to novel means for effecting controlled periodic reversal of the motor. The invention is particularly useful in control of an electric motor-driven mechanism, such as the scanning antenna employed in radio detecting and ranging (radar) systems and the like.

In certain systems of this character, the scanning equipment is driven by an electric motor which is, or may be, periodically reversed so that the scanning equipment is driven back and forth across a desired sector. In addition to this periodic reversal of the motor, means may be provided to permit continuous rotation of the motor and hence continuous rotation of the scanning equipment. A system of this character is disclosed and claimed in a copending application of Frederick R. Farrow, Jr., Serial No. 528,898, filed March 31, 1944. The present invention is in the nature of an improvement of that system.

In some applications of such systems, particularly in the case of a scanning antenna as mentioned above, certain advantages are to be derived from a system in which the continuous rotation of the motor is possible only in one predetermined direction. For example, when some indicating device is associated with the scanning antenna the natural and more easily followed direction of rotation of the indicator is the clockwise direction. Also, one particular direction of continuous rotation of the scanning antenna will usually produce the minimum interference with the gyroscope which is frequently employed with the scanning antenna to maintain the effective axis of rotation of the antenna in some desired position.

It is, therefore, an object of the present invention to provide a simple control arrangement for use with a motor-driven scanning device, by means of which the mode of operation of the scanning device may be changed, at will, from a sector scanning mode of operation to a mode of operation involving continuous rotation in a predetermined sense or direction, and vice versa.

Other objects and advantages of the invention will become apparent during the course of the following description with reference to the accompanying drawings, in which

Fig. 1 is a diagrammatic illustration of a typical control system embodying the principles of the invention;

Fig. 2 is a plan view of an interlocking mechanism employed in accordance with the present invention; and

2

Fig. 3 is a sectional view taken along line 3—3 of Fig. 2.

Referring to Fig. 1, a reversible motor 2 is provided and arranged continuously to rotate, or alternatively, to oscillate, a mechanism such as a directional antenna, or other device, over which control of rotation and period or amplitude of oscillation is desired. In radar practice, structures of this character are commonly known as "spinners" or scanning devices, and such device is so designated in the drawing where it is represented diagrammatically by the circular figure bearing the reference numeral 4. Since the structure and operation of such apparatus is known, and may vary in detail according to the use to which it may be put, the particular apparatus driven by the motor 2 is neither specifically illustrated nor described in detail herein.

The field winding 6 of the reversible motor 2 may be connected directly to the supply line conductors 8 and 10. The armature 12 of this motor is connected to the same line conductors 8 and 10 through the agency of the conductors 14 and 16, 18 and 20, and the reversing relay 22. The reversing relay 22 is preferably of the "over-center" or "latching" type. Reversing relays of this general character are well known in the art, and consequently it is deemed unnecessary to describe this device in detail. It will suffice to say that when the movable contactors 24 and 26 are drawn to the right (as shown) by energization of the relay winding 28 the said contactors will "latch" in that position, and will remain in that position until such time as the relay coil 30 is energized. At such time the contactors 24 and 26 will be drawn to the left, and will remain latched in that position until such time as relay coil 28 is energized. It will be evident from the drawing that the movable contactors 24 and 26, together with the fixed contact points 32, 34, 36 and 38 constitute a conventional reversing switch or relay. Thus, in one position of the movable contactors 24 and 26, the armature 12 of the reversible motor 2 is so connected to the line as to cause rotation of the motor in one direction, while in the other position of the movable contactors 24 and 26, the armature is so connected as to produce motor rotation in the opposite direction.

The armature or rotor 12 of the reversible motor may be mechanically coupled, by any suitable and convenient means, to the scanning device 4. In the drawing, this mechanical coupling is represented by the dashed connecting line. Also mechanically coupled to the reversible motor 2, and rotating in synchronism with the scan-

ning device 4, is a rotating commutator 40, preferably constructed of a conducting material, and bearing a suitable contact element 42. Concentrically arranged around the rotating commutator 40 are a plurality of fixed contact points 44, 46, 48, 50, 52, and 54. These fixed contact points are preferably equally spaced about the rotating commutator, and are so positioned with respect thereto that electrical contact is made between the said fixed contact points and the contact element 42 as the said element rotates past, or reaches, a given contact point. As shown in the drawing, the rotating commutator is connected by means of a conductor 58 to the conductor 18 of the line 8, 18. The specific function of the rotating commutator 40 will be described in detail hereinafter.

Each of the contact points 44, 46, etc., are connected by means of suitable conductors to the similarly designated contact points of a pair of manually operable switches 58 and 60. Thus, by way of example, the contact point 44 associated with the rotating commutator 40 is connected by way of the conductor 62 with the contact point 44a of the switch 60, and by way of the conductors 62 and 64 with the contact point 44b of the switch 58. The switches 58 and 60 together comprise what may be referred to as a "sector selector," and they are so designated in the drawing. Preferably some interlocking means is provided between switches 58 and 60 to prevent switch arm 66 of switch 58 from occupying the same relative position as arm 68 of switch 60. The desirability of this will be explained hereinafter and a preferred interlocking means will be described.

At 90 in Fig. 1 there is schematically illustrated a three-circuit three-position switch and, for explanatory purposes, the three positions, namely "On," "Trip," "Off," of the rotatable member of the switch are separately shown. This switch may be referred to as the sector scanning "On-Off" switch. One circuit of switch 90 comprises contacts *a* and *b*, another circuit comprises contacts *c* and *d* and the third circuit comprises contacts *e* and *f*. The rotatable member of the switch comprises the three segments *u*, *v* and *w*, of conducting material, suitably mounted and insulated from each other. For simplicity, specific connections to the switch contacts are shown for only the "On" position. Also, it is to be noted that although there are three electrical positions, "On," "Trip," "Off," for switch 90, it is preferable that only two mechanical positions, namely, "On" and "Off," be incorporated in the construction of the switch.

In the "On," or sector-scanning, position of the switch 90, the adjustable contact arm 66 of switch 58 is connected by way of conductor 70, one circuit (contacts *a* and *b*) of the three-circuit switch 90, and conductor 71 to terminal 82 of the reversing relay coil 28. Similarly the adjustable contact arm 68 of switch 60 is connected by way of conductor 72, one circuit (contacts *c* and *d*) of switch 90, and conductor 73 to terminal 78 of reversing relay coil 30. The third circuit of switch 90, comprising contacts *e* and *f*, is arranged so that one contact, *e* in Fig. 1, is connected by conductor 102 to the same side of the supply line conductors 8, 18 that is connected to the rotating commutator 40. The other contact *f* is connected by the jumper connection 104 to contact *d*, as shown in Fig. 1, or, alternatively, to contact *b*. The other terminals 84 and 80 of coils 28 and 30 are connected together by means of conductor 74 and to the line conductor 8 by way of conductor 76. 75

Accordingly, one terminal of each reversing relay coils 28 and 30 is connected permanently and directly to one side of line 8, 18. For sector scanning, connection between the other terminals of the coils 28 and 30 and the other side of the line is made through the sector scanning "On-Off" switch 90, the sector selector switches 58 and 60, and the rotating commutator 40. Where continuous rotation of the scanning device 4 is desired, the switch 90 is employed in a manner to be described hereinafter.

The component parts and connections illustrated in Fig. 1 having now been described, the operation of the system will now be set forth, assuming the sector scanning "On-Off" switch 90 is in the "On" or sector scanning position. Let us assume that it is desired to so operate the scanning device 4 that the sector S_1 shall be continuously scanned. As indicated, the limits of the sector S_1 are defined by the reference characters 44c and 46c. By means of the structure provided, such operation is secured by setting the contact arms 66 and 68 of sector selector switches 58 and 60 to corresponding and similarly designated switch contact points.

Thus the contact arm 66 may be adjusted to contact the contact point 44a, while the contact arm 68 is adjusted to contact the contact point 44b. These switch adjustments are illustrated 30 in the drawing. If now the field 2 of the motor 2 is connected in the proper sense to the line conductors 8 and 18, and this is most conveniently determined by trial, the system will operate as follows. Assume that at the instant represented in the drawing the scanning device 4 and the rotating commutator 40 are being driven synchronously in a clockwise direction by the reversible motor 2. When the contact element 42 of the rotating commutator reaches the contact point 46, a connection will be completed 40 between the line conductor 18 and the terminal 78 of relay coil 30. This connection includes the conductor 58, the rotating commutator 40, contact element 42, contact point 46, conductor 86, contact point 46a, switch arm 66, conductor 72, contact *c*, segment *v*, contact *d*, and the conductor 73. Since terminal 86 of the relay coil 30 is already connected to the other side of the line by way of the conductors 74 and 78, the coil 30 is now energized from the line, and consequently the movable contactors 24 and 26 are moved from the position illustrated to their left-hand position, where they make contact with stationary contacts 32 and 36 respectively, thus reversing the connections between the armature 12 and the line conductors 8, 18, and thereby reversing the direction of rotation of the motor. The direction of rotation of the scanning device 4 and the rotating commutator 40 are, of course, also reversed, and consequently the rotating commutator 40 now proceeds to rotate in a counter-clockwise direction. This it continues to do until the contact element 42 reaches and makes contact with contact point 44. When this occurs a connection is completed between the line conductor 18 and terminal 82 of relay coil 28. This connection includes the conductor 58, the rotating commutator 40, contact element 42, contact point 44, the conductors 82 and 84, switch arm 68, conductor 70, contact *a*, segment *u*, contact *b*, and the conductor 71. Since the terminal 84 of relay coil 28 is already connected to line conductor 8 by way of the conductors 74 and 78, the coil 28 is energized and movable contactors 24 and 26 are moved from their left-hand

position to the right-hand position shown. This effects a second reversal of the motor 2, whence the scanning device 4 and the rotating commutator 48 are also reversed and begin rotation in the clockwise direction. The foregoing train of events will now repeat cyclically so long as the contact arms 66 and 68 of the sector selector switches remain in the positions shown.

It will now be evident that it is possible to establish, on the sector selector switches 58 and 68, connections corresponding to desired sector limits on the scanning device 4, and thus to effect continuous scanning over a desired sector. For example, if it is desired to sector-scan the sector S₂ included within the sector limits 52c and 54c, it is only necessary to adjust the switch arm 66 to contact the contact point 52b and to adjust the switch arm 68 to contact the contact point 54a. Larger sectors may be scanned by adjusting the switch arms 66 and 68 to the contact points corresponding to the limits of the desired sector. Where six contact points are provided, as in the illustration, the smallest sector which can be scanned is a 60° sector. If smaller sectors are desired it is, of course, necessary only to increase the number of contact points associated with the rotating commutator and with the two sector selector switches.

Although it will normally be desired to scan sectors of substantially less than 180°, it may, under certain circumstances, be useful to scan sectors of greater than 180°. Such large sectors are as readily scanned with the apparatus illustrated as are the smaller sectors. As has already been stated, with the specific adjustment illustrated in the drawing, sector scanning of the device 4 is effected over the sector S₁. If, now, the relative positions of the sector selector switches are reversed, i. e., if contact arm 66 is moved to contact 46b and contact arm 68 moved to 44a, the scanning device 4 will sector-scan the sector S₃. It will be observed that the sector S₃ has the same limits as the sector S₁, but that sector S₃ is the complement of sector S₁.

The scanning apparatus of the drawing has been described, so far, only with reference to its operation as a sector scanning system. As was indicated at the outset, the system illustrated in the drawing is also adapted to effect continuous rotation, in one predetermined direction, of the scanning device 4. The selection of sector scanning or of continuously rotation in one predetermined direction is accomplished, in accordance with the present invention, by means of the sector scanning "On-Off" switch 90. As previously stated, sector scanning is effected by placing switch 90 in the "On" position whereby contacts *a* and *b* are connected together by segment *u* and contacts *c* and *d* are connected by segment *v*. In this position of switch 90 contacts *e* and *f* are in an open circuited relationship. In the description of switch 90 it was stated that, although there are preferably but two operating positions for this switch, there are three electrical positions for switch 90. The switch mechanism is so arranged that in turning the switch from "On" to "Off" or from "Off" to "On" the rotatable member of the switch passes through the intermediate or "Trip" position. For continuous rotation of the scanning device 4 the sector scanning "On-Off" switch 90 is turned to the "Off" position. This operation of switch 90 momentarily places the movable element of the switch in the "Trip" position indicated in Fig. 1. When the segments *u*, *v* and *w* occupy the positions corre-

sponding to this "Trip" position, the continuity of the circuits from sector selector switches 58 and 68 to the reversing relay coils 28 and 30 is opened at contacts *a* and *b* and *c* and *d* of switch 90 by movement of segments *u* and *v*. Thus sector selector switches 58 and 68 cannot now energize reversing relay coils 28 and 30. Also as switch 90 passes through this "Trip" position the segment *w* of switch 90 connects contacts *e* and *f* together, thereby effectively connecting terminal 18 of coil 28 to conductor 18 of line conductors 8, 18 and energizing coil 28 to place contactors 24 and 26 in their left-hand position. Motor 2 will then rotate in the direction corresponding to this position of contactors 24 and 26. If the direction of continuous rotation is to be in the reverse direction, changing jumper 104 from contact *d* to contact *b* will result in coil 28 being energized when switch 90 is turned from "On" to "Off." The contactors 24 and 26 will then be drawn to their right-hand position and motor 2 will run continuously in the corresponding direction.

Since the reversing relay 22 is of "over-center" or "latching" type, it is unnecessary to continuously excite either of the relay coils to keep contactors 24 and 26 in position. Thus when switch 90 reaches its "Off" position, all three circuits of the switch are open circuited as indicated in the "Off" position for switch 90 in Fig. 1. This position of switch 90 prevents further excitation of the reverse relay coils 28 and 30.

To return to sector scanning, switch 90 may be turned back to its "On" position. Going through the "Trip" position again will, of course, have no effect upon the reversing relay 22 since the contactors 24 and 26 are already in the position determined by switch 90 as it previously swept through the "Trip" position. It is evident then that only two operating positions, namely "On" and "Off," are required for a dial indicator for switch 90.

When operating the system for sector scanning, it is desirable to avoid simultaneous excitation of both coils 28 and 30 of the reversing relay 22. Accordingly, some interlocking means should preferably be provided between sector selector switches 58 and 68 such that switch arms 66 and 68 cannot rest on corresponding switch contacts at the same time. To provide this interlocking feature, the switches 58 and 68 may be of the "ganged" type in which switch arms 66 and 68 are separately adjustable by individual control knobs through a concentric drive shaft arrangement. The interlocking may be accomplished by means of a pin and arcuate slot connection between the two control knobs, where, for example, a pin in one control knob travels in a slot in the other control knob. An interlocking means of this type is illustrated in Figs. 2 and 3, which show only those parts of the sector selector switch which embody the interlocking means, since the sector selector switch itself may be a conventional twin switch structure arranged for concentric drive operation.

Referring to these figures, a control knob 11 for one of the switch arms of the sector selector switch has a pin 13 extending into a slot 15 in the other switch arm control knob 17. The control knobs 11 and 17 are suitably mounted on the concentric drive shaft mechanism 19 of the sector selector switch. Element 21 represents a dial plate for the position indication of control knobs 11 and 17.

As shown in Fig. 2, the relative positions of the switch arms may be indicated by the pointers

23 and 25 on the control knobs 11 and 17. The radial line sections on indicator plate 21 represent the radial locations of an arbitrary number of switch contacts.

From the illustration it is evident that the length of slot 18 determines the extent of relative motion between the two control knobs 11 and 17, and hence the extent of relative motion between the switch arms 66 and 68 of the sector selector switch. As shown in Fig. 2, the control knob 11 is in its maximum counter-clockwise position with respect to control knob 17 due to pin 13 engaging the end of slot 18. The control knob 11 may be moved clockwise relative to knob 17 until pin 13 strikes the other end of slot 18. In either of these limiting positions there will be a relative distance of one contact between the two pointers 23 and 25 or between the two switch arms of the switch to which the drive mechanism 19 is connected, thus preventing both switch arms from occupying the same relative position. The control knobs 11 and 17, may, of course, be so adjusted that one switch arm may be placed on any desired contact while the other switch arm may rest on any other non-corresponding contact.

The pin and slot connection between the two knobs has the further advantage that both of the switches may be set by manually moving knob 11 in one direction so as to set knob 17 and then moving knob 11 in the opposite direction to set it. In similar manner both switches could be set by moving knob 17. Thus both switches may be set by grasping only one of the knobs and moving it in the manner indicated.

It will be apparent that the invention is not limited to the specific purpose illustrated and described, but may be utilized in any instance to effect continuous rotation in one predetermined direction of an adjustable periodic reversing motor driven equipment. It will also be apparent that various modifications within the scope of my invention will occur to those skilled in the art. Therefore, I do not limit it to the specific form and arrangement of the apparatus diagrammatically illustrated in the drawings.

I claim:

1. In an apparatus for controlling sector scanning equipment, a driving motor, scanning equipment driven by said motor, rotary switching means driven by said motor synchronously with said scanning equipment, manually-settable selector switching means for determining the location and amplitude of the sector to be scanned, means controlled by both of said switching means to cause reversing of said motor automatically as said scanning equipment reaches the limits of the scanned sector, a manually-operable switch for rendering the aforesaid switching means inoperative at will to interrupt the sector scanning, and means controlled by said manual switch for actuating said motor-reversing means so as to cause continuous operation of the motor in a single predetermined direction, thereby to actuate said scanning equipment continuously in said direction.

2. In an apparatus for controlling sector scanning equipment, a driving motor, scanning equipment driven by said motor, rotary switching means driven by said motor synchronously with said scanning equipment, manually-settable selector switching means for determining the location and amplitude of the sector to be scanned, an electrically-operable reversing switch controlled by both of said switching means to cause

reversing of said motor automatically as said scanning equipment reaches the limits of the scanned sector, a manually-operable switch for rendering the aforesaid switching means inoperative at will to interrupt the sector scanning, and means controlled by said manual switch for actuating said reversing switch so as to cause continuous operation of the motor in a single predetermined direction, thereby to actuate said scanning equipment continuously in said direction.

3. In an apparatus for controlling sector scanning equipment, a driving motor, scanning equipment driven by said motor, rotary switching means driven by said motor synchronously with said scanning equipment, manually-settable selector switching means for determining the location and amplitude of the sector to be scanned, an electrically-operable reversing switch controlled by both of said switching means to cause reversing of said motor automatically as said scanning equipment reaches the limits of the scanned sector, said reversing switch comprising movable contact means and a pair of actuating coils for moving the contact means between two positions, the contact means being adapted to remain in either position when actuated theretc, a manually-operable switch having on and off positions and adapted to control the sector scanning, and means operable by said manual switch during its movement from its on position to its off position for momentarily energizing a predetermined one of said coils to cause continuous operation of the motor in a single predetermined direction, thereby to actuate said scanning equipment continuously in said direction.

4. In an apparatus for controlling sector scanning equipment, a driving motor, scanning equipment driven by said motor, rotary switching means driven by said motor synchronously with said scanning equipment, a pair of manually-settable selector switches for determining the location and amplitude of the sector to be scanned, the limits of the sector being determined by the respective settings of said selector switches, interlocking means for preventing said selector switches from being set in similar positions, and means controlled by the aforesaid switching means and switches for reversing said motor automatically as said scanning equipment reaches the limits of the scanned sector.

5. In an apparatus for controlling sector scanning equipment, a driving motor, scanning equipment driven by said motor, rotary switching means driven by said motor synchronously with said scanning equipment, a pair of manually-settable selector switches for determining the location and amplitude of the sector to be scanned, the limits of the sector being determined by the respective settings of said selector switches, coaxially-related control knobs for said selector switches, a pin and slot connection between said knobs for preventing said selector switches from being set in similar positions, and means controlled by the aforesaid switching means and switches for reversing said motor automatically as said scanning equipment reaches the limits of the scanned sector.

6. Apparatus for actuating a rotatable device back and forth through any one of a plurality of predetermined sectors or for rotating said device continuously in one predetermined direction, comprising a reversible motor connected to said device to drive the same, rotary switching means driven by said motor synchronously with said device, said switching means including a rotating

contact and a plurality of fixed contacts engageable by said rotating contact, a manually-adjustable sector selector device having fixed contacts corresponding to those of said rotary switching means, and also having rotatable contact means adapted to be placed in engagement with the associated fixed contacts, electrically-operable means for effecting reversal of operation of said motor, circuit connections between said rotary switching means, said sector selector device and said reversing means for controlling the latter so as to effect actuation of said rotatable device through a sector determined by the setting of the sector selector device, and manually-operable switch means included in said circuit connections for interrupting the sector operation of said rotatable device and for conditioning said reversing means so as to effect operation of said rotatable device continuously in one predetermined direction.
